UNITED STATES PATENT OFFICE.

HAROLD L. WARWICK, OF FORT WORTH, TEXAS.

TELEPHONE-CALL RECORDER.

1,041,536.

Specification of Letters Patent.

Patented Oct. 15, 1912.

Application filed April 15, 1912. Serial No. 690,989.

To all whom it may concern:

Be it known that I, HAROLD L. WARWICK, citizen of the United States, residing at Fort Worth, in the county of Tarrant and State 5 of Texas, have invented certain new and useful Improvements in Telephone-Call Recorders, of which the following is a specification.

My invention relates to telephone recording devices and more particularly to devices 10 to be used with established telephone exchanges, and the object is to provide simple and inexpensive devices to be located at any subscriber's telephone and which can be operated from the central office and which 15 operates automatically when the connection is made at the central office.

The advantages are that when the line is 20 busy, the operator at the telephone exchange can record the number of the party calling in the office of the party who is talking so that the party can see who has called while he was talking. In this manner a person will not have to call repeatedly and be told 25 that "the line is busy." He can call and if the line is busy, he can wait and attend to other business and know that he will be called as soon as the party leaves the line. This will save time of the person who wants 30 to call and save time of "central." If a person calls and "central" answers,—"No one answers," "central" or some other operator can record the call at the telephone where no one answered. This will be a 35 great advantage in offices where there is no one to answer the call. When a subscriber returns to his office, he can see who has called while he was out. Central, or the operator who attends to the recording mechanism, can record a number at the 40 subscriber's telephone without in any manner disturbing the conversation which the subscriber may be carrying on over the telephone. The addition can be made to the 45 established telephone system with very small expense as there will be very little more wiring.

Other objects and advantages will be fully explained in the following description and 50 the invention will be more particularly pointed out in the claims.

Reference is had to the accompanying drawings which form a part of this application.

55 Figure 1 is a diagrammatic view, illustrating the complete device assembled, some

parts being in conventional form. Fig. 2 is a detail view of the type-wheel ratchet releasing mechanism. Fig. 3 is a detail view of the contacts in the sending mechanism. 60 Fig. 4 is a detail view of the train of gearing used in the sending device. Figs. 5 and 6 are detail views of the keys of the sending device. Fig. 7 is an enlarged section of the record tape. Fig. 8 is a detail view of the 65 magnets for effecting the printing and also a view of the type-wheel and the spring for returning the type-wheel to normal position.

Similar characters of reference are used 70 to indicate the same parts throughout the several views.

The sending mechanism includes a series of push buttons,—one button for each one of the ten digits and a button for indicating 75 each exchange and one button for long distance. Each button 1 is provided with a stem 2 and a spring 3 for returning the button to normal or inoperative position. Each stem 2 is pivotally connected to a crank 4 80 which is rigid with a shaft 5 which operates a train of gearing of ordinary type and this gearing will not be described in detail. A push on a button will wind a spring 6 to sufficient tension to actuate the 85 train of gearing. This train of gearing terminates with an impulse sending wheel 7. Each impulse wheel is provided with one or more teeth or projections 8 and one projection 9 on the periphery thereof and these 90 projections constitute contacts for actuating the type wheel hereinafter described. The difference between projection 9 and the projections 8 is that the projection 9 is longer and insulated from wheel 7 and will make 95 a different connection for sending an impulse with a greater voltage than will be sent by the contacts 8. The sending device or mechanism is indicated by 10. The sending mechanism is operated through the telephone switch board or exchange and may be operated by central or some operator designated for such work. The sending mechanism is connected to a supply source of electricity, as to batteries 62, by a wire 63 which 100 is connected to a portion of the batteries 11 and to the frame of the sending mechanism 10. An insulated contact 13 is provided in the sending mechanism and stands in the path of the projections 8 of the impulse 110 wheel 7. This contact 13 is connected by wire 14 to a plug 15 which is used to make

connection with any subscriber's telephone which is connected with the multiple 16. A line 17 is shown leading from the multiple or exchange to a subscriber's telephone which is supplied with a recording device. 5 The object of the contact or projection 9 is to change the voltage which passes through the wire 17. The projection 9 will press a contact 19 against the contact 13. The contact 19 is connected to all of the batteries 62 so that, if the batteries consist of six cells and three cells are connected with the wire 63 for sending impulses through contact 13 and all the cells are connected in the circuit 10 with the contact 19, the voltage will be doubled when the circuit is switched from the circuit through the wire 63 to the circuit through wire 18. Thus the wheel 7 will send an impulse of the lower voltage 15 through the contact 13 whenever one of the teeth 8 passes the contact 13 and when the contact passes the contact the higher voltage will be sent through the contact 19 and then through the contact 13. The impulses will 20 actuate the recording mechanism hereinafter 25 described.

The recording mechanism is shown in Fig. 1. A wire 20 is connected with a binding post 21 and the binding post 21 is connected 30 by a wire 22 with the magnet 23. The binding post 21 is also connected by wire 24 to an armature 25 which will be drawn to the magnet 23 whenever this magnet is energized. A spring 26 is used to restore the 35 armature 25 to normal position as soon as the magnet 23 is deenergized. A screw 27 is used to regulate the tension of the spring 26. The recording mechanism is provided with a type-wheel 28 on the periphery of 40 which are formed digits and letters. This wheel is actuated by a ratchet wheel 29 rigid therewith. The armature 25 carries a dog 30 which is adapted to engage the teeth on the ratchet wheel 29 and will turn this 45 ratchet wheel and the type-wheel 28 one space with every movement of the armature 25 toward the magnet 23. This will be done every time an impulse is sent through the magnet 23. A cam 31 on the dog 30 will de- 50 tach the dog 30 from the ratchet wheel whenever the cam 31 rides up on the lug 32. Adjusting screws 33 limit the movement of the armature 25. An inking roller 34 is provided with means for spreading ink on the 55 type of the wheel 28. The dog 30 will actuate the type-wheel 28 as long as impulses are sent by the teeth 8 without recording any number, but when the tooth or contact 9 sends an impulse the dog will move the 60 type-wheel one space or type just as when the impulses were sent by teeth 8. At the same time, on account of the higher voltage sent by the contact 9, the current will be switched out of the magnet 23 to the magnet 65 35. Magnet 35 will attract the armature

36 which is mounted on bar 45 which is pivotally mounted. On the other end of the bar 45 is mounted a hammer 37 which will strike the type-wheel 28 and drive a strip of paper 38 against the type on the periphery thereof and thus print the digit to be printed. The paper strip 38 is drawn from a spool 39 and is drawn off by two rollers 40 which are driven by a ratchet wheel 41 which is rigid with one of the wheels 40. 70 The dog 41 is operated by the pivoted bar 45. An arm 42 is carried by the bar 45 and a spring dog 43 is pivotally connected to the arm 42 and held against the wheel 41 by a spring 44. The movement of the bar 45 will operate the dog 43. A spring 46 will restore the bar 45 to normal position and the tension of this spring is regulated by a screw 47. The current is switched from the magnet 23 to the magnet 35 when the contact 48 carried by the armature 25 is drawn in contact with the screw 49 which is electrically connected with the magnet 35 by a wire 50. The magnet 23 is electrically connected with the magnet 35 by a wire 51. 80 The stronger voltage sent by the tooth or contact 9 will cause the armature to close the circuit through the contact 48 to magnet 35. The current is grounded by a wire 53 which connects with a binding post 54 which is connected to the wire 50 by a wire 55. An adjusting screw 56 is used to control the movement of the bar 45. A spring dog 57 prevents the ratchet wheel 29 from turning when the dog 30 is riding over the teeth 8 and 9 and a notched wheel 58 on the wheel 40 is used to release the dog 57 so that the wheel 29 can be turned by the dog 30 when the wheel 40 is rotated. The type wheel 28 and the ratchet wheel 29 are rigid on the same shaft and the type wheel is brought back to normal position by a spring 59. A pin 60 which is rigid in the casing stops the type wheel at normal position. The type wheel 28 has a lug 61 which abuts against 90 the pin 60.

In operation the sending device is actuated by pushing the button for each digit which makes up the number of the telephone wanted. The wheel 7 is rotated and every 115 tooth 8 on the wheel will send an impulse which will cause the type wheel to rotate one space or the distance of one type. The current for sending the impulses comes from the source of electricity through the frame of the sending mechanism. Batteries or cells 62 are shown electrically connected to the frame by a wire 63 which will feed from only half of the battery cells. When the tooth 9 passes the current comes from all 120 the cells 62 and thus sends a greater voltage through the wire 14. This will cause the dog 30 to move the type wheel 28 into position to print the number wanted. At 125 the same time the armature 25 will make 130

contact or close the circuit through contact 49 and thus switch the current from magnets 23 to the magnet 35 by which the hammer 37 is made to knock the paper 38

- 5 against the type on wheel 28. Any suitable type of digits and letters may be formed on the periphery of wheel 28 to register calls made. If no teeth 8 are on wheel 7, a push on the button would record a "0." 10 If the wheel 28 has one tooth 8, a push on the corresponding button would record "1," etc. It is apparent that various arrangements of the operating mechanism and the digits and the letters can be made without departing from my invention.

What I claim, is,—

1. A telephone call recorder comprising a multiple switch-board, line circuits connected thereto, local stations on said line circuits, an impulse sending mechanism consisting of a plurality of graduated operating elements any one of which is provided with means for connecting with any unit of said switch board, and including a wheel 20 carrying means for switching from a lower voltage in said circuits to a higher voltage, and means at the local station for recording the impulses sent over said line wires.

2. A telephone call recorder comprising a multiple switch-board, line circuits connected thereto, local stations on said line circuits, an impulse sending mechanism consisting of a plurality of independent graduated operating elements any one of which is provided with means for connecting with any unit of said switch-board and including a plurality of contacts acting successively and the last contact doubling the voltage, and means at the local station for recording 35 the impulses sent over said line wires.

3. A telephone call recorder comprising a multiple switch-board, line circuits connected thereto, local stations on said line circuits, an impulse sending mechanism consisting of a plurality of independent operating elements for sending one or more impulses and each element including contacts corresponding to impulses to be sent and the last contact doubling the voltage, means for connecting any one of said elements to said switch board, and means at the local stations for recording the last impulse sent over said line circuits by each one of said operating circuits.

4. A telephone call recorder comprising a multiple switch-board, line circuits connected thereto, local stations on said line circuits, an impulse sending mechanism consisting of a plurality of independent operating elements each including a rotatable wheel and a contact maker for lower voltage and a contact maker for higher voltage coöperating with said wheel for sending one or more impulses over any one of said line wires, means 60 for connecting any one of said operating ele-

ments with any unit of said switch-board, and means at the local station for recording impulses sent over said line wires.

5. A telephone call recorder comprising a multiple switch-board, line circuits connected thereto, local stations on said circuits, an impulse sending mechanism consisting of a plurality of independent operating elements each including a rotatable wheel and means coöperating with said wheel for sending currents of different voltage over said line circuits, means for connecting any one of said operating elements to any unit of said switch-board, and means at a local station for recording impulses sent over the line circuit to said station.

6. The combination with a multiple switch-board and line circuits and local stations of a sending mechanism consisting of a plurality of independent operating elements for sending one or more impulses over said line circuits each operating element including a rotatable wheel and each wheel except one being provided with means for sending currents of different voltage over said line circuits, means for connecting any one of said operating elements to any unit of said switch-board, and means at each local station for recording impulses sent over the line circuit.

7. A telephone call recorder comprising a multiple switch-board, line circuits and local stations, a selective sending mechanism adapted to be connected to said switch-board, means at a local station for recording impulses sent over the line circuit including a type wheel, and electrical devices actuated by currents through said line circuit for rotating said wheel and electrical devices for operating said recording mechanism after said wheel stops rotating.

8. A telephone call recorder comprising a multiple switch-board, line circuits and local stations connected therewith, a sending mechanism adapted to be connected to said switch-board, recording mechanism at a local station for recording impulses sent over said line circuit including a type-wheel and printing devices, electrical devices actuated by currents from the line circuit for operating said recording mechanism, said sending mechanism including means for causing said electrical devices to actuate said type wheel without printing until the desired digit is brought into position and then to actuate the printing devices.

9. A telephone call recorder comprising a multiple switch-board, line circuits and local stations connected therewith, a sending mechanism adapted to be connected to said switch-board, recording mechanism at a local station for recording impulses sent over the line circuit including a type wheel and printing devices, electrical devices including a magnet actuated by currents over said line circuit for rotating said type-wheel and elec-

- 4
- trical devices including a magnet actuated by currents sent over said line circuit for operating said printing devices, said sending mechanism including means for causing one magnet to rotate said type-wheel until the desired digit is brought into position and then for switching the current over the line wire to the other magnet for operating the printing mechanism.
- 5 10. A telephone call recorder comprising a multiple switch-board, line circuits and local stations connected therewith, a sending mechanism adapted to be connected to any unit of said switch-board, recording mechanism at a local station for recording impulses sent over the line circuit including a type wheel and printing devices and paper feeding devices, electrical devices including a magnet actuated by currents over said line
- 15 20. circuit for rotating said type-wheel and electrical devices after the type wheel stops rotating including a magnet actuated by currents sent over said line circuit for operating said printing devices and paper feeding
- 25 devices, said sending mechanism including means for causing one magnet to rotate said wheel until the desired digit is brought into position and means for switching the current over the line circuit to the other magnet
- for operating said printing devices and paper feeding devices. 30
11. A telephone call recorder comprising a multiple switch-board, line circuits and local stations, a selective sending mechanism adapted to be connected with said switch-board, means at a local station for recording impulses sent over the line circuit including a type wheel and printing devices, two sets of electrical devices operatively connected to the line circuit and operated by currents over the line circuit, and members actuated by said sending mechanism for sending a current of lower voltage over the line circuit for operating one set of said electrical devices for rotating said type wheel until the desired digit is brought into position and then for switching to send a higher voltage over the same circuit for operating the other set of electrical devices to effect the recording of the digit. 35 40 45 50

In testimony whereof, I set my hand in the presence of two witnesses, this 12th day of April, 1912.

HAROLD L. WARWICK.
